UNITED STATES PATENT OFFICE.

FRANK ROBINSON, OF BANGOR, MAINE, ASSIGNOR TO THE ROBINSON COMPANY, OF BANGOR, MAINE, A CORPORATION OF MAINE.

CLAMP-ANCHOR.

No. 888,931.

Specification of Letters Patent.

Patented May 26, 1908.

Application filed April 1, 1907. Serial No. 365,661.

To all whom it may concern:

Be it known that I, FRANK ROBINSON, of Bangor, in the county of Penobscot and State of Maine, a citizen of the United States, 5 have invented a new and useful Improvement in Clamp-Anchors, of which the following is a full, clear, and exact description, reference being had to the accompanying drawings, forming a part of this specification, in 10 explaining its nature.

My invention relates to what may be termed a clamp anchor especially adapted to grip onto a rail for fastening thereto a cable, chain or other means of connection.

15 It often becomes necessary in railroad work to attach a cable or chain to a rail acting as a base of support. To do this the usual custom has been to wrap a chain around the rail and thus fasten a cable or other connection to the wrapped chain. To wrap a chain around a rail not only takes considerable time, both for wrapping and unwrapping the chain, but under some circumstances it is 20 rather a dangerous expedient to resort to on account of passing trains. Then again when the road-bed is frozen it is an exceedingly difficult matter to apply the chain to the rail, to say nothing of the inexpediency of disturbing the roadbed at such a time.

25 The clamp anchor forming the subject matter of my invention overcomes all these difficulties above referred to and provides a means which may not only be quickly applied to or disconnected from a rail, but it is 30 also designed to provide such means as will grip the rail with an increasing power of resistance in case there is any tendency for the anchor to slip.

The anchor can best be seen and understood 35 by reference to the drawings, in which—

Figure 1 represents the device in front elevation. Fig. 2 shows a cross section of the same on the line 2—2 of Fig. 4. Fig. 3 shows the anchor in side elevation. Fig. 4 shows a 45 plan of the same. Fig. 5 shows a section on the line 5—5 of Fig. 3.

In the drawings:—A represents a portion of a rail of which a is the head and a¹ the shank of the rail.

50 B represents the clamp anchor which forms the subject matter of my invention. The anchor B comprises a body portion b which rests squarely upon the top surface of the head of the rail. Dependent from this

body and enveloping the head of the rail on either side thereof are separate flanges or cheeks b¹, b². Of these the flange b¹ is adapted to fit snugly against the side of the head of the rail and is provided with a projecting lip b³ which is adapted to fit underneath the head of the rail on one side thereof and preferably projects to contact with the shank of the rail.

The flange b² depends from the body of the anchor at a point some little distance removed from the head of the rail, or in other words, so far removed therefrom that the anchor may by a lateral application be applied to the rail with the lip b³ extending under the head thereof as before described. 65 By reason of the distance which separates the flange b² from the head and shank of the rail there is therefore formed between such parts a socket b⁴, which as may be seen by reference to Fig. 5, gradually narrows or contracts away from the forward end of the anchor. Such contraction is formed by gradually narrowing the body of the device from 70 its forward end, as may be seen in Fig. 4. In the socket b⁴ is contained a wedge-shaped locking bar or key b⁵ which as may be seen in Fig. 5, is, like the socket in which it is contained, made gradually narrowing away 75 from its forward end, or in other words, the end thereof corresponding with the forward end of the anchor. The locking bar b⁵ is held in place by means of a lip b⁶ which projects from the end of the flange b² and fits into a recess or incision b⁷ made in the bar. This lip also affords means whereby the 80 flange may grip the locking bar or wedge. The inner side or face of the locking bar b⁵ is made to fit snugly against the shank and under side of the head of the rail and moreover with a large contacting surface in order 85 that a large degree of frictional resistance may be obtained between the bar and the rail. The outer side or face of the bar contacts with the ends of a plurality of threaded bolts b⁸ which extend through the flange b². 90 In other words, instead of contacting with the inner surface of the cheek forming one side of the socket in which the locking bar b⁵ is contained, it bears against the ends of the bolts b⁸ on which account a slight space will 95 separate the outer side or face of the locking bar from the adjacent inner side or face of the flange.

100 105

On the forward end of the anchor directly over the rail there is placed a projecting boss b^9 . To this boss is attached a clevis b^{10} by means of a pin b^{11} . To the clevis b^{10} is 5 adapted to be attached the cable or chain for which the clamp anchor secured to the rail furnishes a means of interposed connection.

The operation of the anchor is as follows:

After the body of the anchor has been 10 applied to rest squarely upon the rail with the flange b^1 and lip b^3 engaging one side thereof, the locking bar b^5 is slipped in between the other flange b^2 and the side of the rail, the lip b^6 acting to hold the locking bar 15 primarily in place. At this time the bolts b^8 are screwed so far into the flange b^2 that the forward ends of the bolts will project slightly and a uniform distance forward from the inner side or face of the flange and the locking bar b^5 will be interposed so far into its 20 socket that it will contact on the one side with the rail and on the other side with the ends of these projecting bolts, so that, as said before, a slight space will separate the 25 outer face of the locking bar from the adjacent inner side or face of the flange. The bolts are then uniformly tightened, by which stress the locking bar is pressed hard up against the side of the rail contacting with 30 the shank thereof and under side of the head of the rail, as before explained. The anchor thus becomes firmly secured to the rail and by a connection which will withstand any ordinary strain upon it. In case the stress 35 or strain becomes too intense so that there is developed a tendency for the anchor to slip, such slipping will be immediately arrested, for when the anchor begins to slip its tendency will be to draw over the wedge-shaped 40 locking bar b^5 , which remains in a stationary position by reason of its frictional engagement with the side of the rail. As the body of the anchor draws over the locking bar b^5 it will not only become wedged thereon, but 45 the bar itself by such action will be forced more firmly against the side of the rail. Therefore inasmuch as the locking bar is wedged against the side of the rail with such force that it cannot slip and inasmuch, also, 50 as the body of the anchor cannot draw over the locking bar, the effect is that the anchor becomes locked upon the rail with a degree of retention commensurate with the strain to which it is subjected.

55 To release the device it is only necessary to loosen the bolts b^8 when the locking bar may be slipped out of its socket and the anchor removed from the rail. In this connection it is to be observed that it is by 60 reason of the locking bar having a releasable bearing that such release of the anchor is so expeditiously obtained. If the locking bar contacted with the irreleasable face of its adjacent flange then while the anchor would 65 become firmly secured to the rail and more-

over with a gradually increasing degree of retention as before described, it would be a difficult matter to disconnect it from the rail, but by having the locking bar engage with releasable surfaces or points the release 70 of the locking bar and consequent unlocking of the anchor from the rail becomes a very simple matter.

Having thus fully described my invention, I claim and desire to secure by Letters Pat- 75 ent of the United States:—

1. A device of the character specified having a body portion adapted to be mounted lengthwise upon a rail, means whereby said body may connect with the rail beneath the head on one side thereof, a flange dependent from said body which when said device is in an operative position is adapted to assume a position removed from said rail on the other side thereof from the side aforementioned, a 80 wedge adapted when said device is in an operative position to be located between said flange and the rail, said wedge extending longitudinally alongside said rail and formed in part to fit snugly beneath the head thereof, 85 means for supporting said wedge from said flange, and releasable members extending through said flange and providing a releasable lateral bearing for said wedge.

2. A device of the character specified having a body portion adapted to be mounted lengthwise upon a rail, means whereby said body may connect with the rail beneath the head on one side thereof, a flange dependent from said body which when said device is in 90 an operative position is adapted to assume a position removed from said rail on the other side thereof from the side aforementioned, a wedge adapted when said device is in an operative position to be located within a 95 socket formed between said flange and the rail, said wedge extending longitudinally alongside said rail and formed in part to fit snugly beneath the head thereof, a lip projecting from said flange and fitting in a longitudinal recess formed in said wedge, and releasable members extending through said flange to contact with the side of said wedge 100 providing a releasable lateral bearing therefor, substantially as described.

3. A device of the character specified having a body portion adapted to be mounted upon a rail, a flange dependent from said body of the device and adapted when said device is in an operative position to envelop 105 and grip said rail beneath the head on one side thereof, a flange dependent from said body of the device and adapted when said device is in an operative position to assume a position removed from said rail on the other 110 side thereof, a key comprising a wedge-shaped member supported to lie when said device is in an operative position interposed between said removed flange and said rail beneath the head thereof, and a series of re- 115

leasable members extending through said flange and providing a releasable lateral bearing for said key.

4. A device of the character specified comprising a body portion b adapted to rest upon a rail, a flange b^1 dependent from said body of the device and adapted when said device is in an operative position to grip said rail upon one side beneath the head thereof, a flange b^2 dependent from said body and adapted when said body is in an operative position to assume a position removed from

said rail on the other side thereof, a wedge-shaped member b^5 supported by said flange b^2 and interposed between the same and said rail beneath the head thereof, and a series of releasable members extending through said flange b^2 and providing a lateral bearing for said wedge-shaped member. 15
